CLAIM

The ornamental design for a notebook cover, as shown and described.

DESCRIPTION

FIG. 1 is a front and top perspective view of a notebook cover showing my new design;

FIG. 2 is a rear and bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top view thereof; and,

FIG. 8 is a bottom view thereof.

The broken lines depict environment and form no part of the claimed design.

1 Claim, 8 Drawing Sheets(56)
